UNITED STATES PATENT OFFICE

PASQUALE GALASSI, OF NEW YORK, N. Y.

MULTIPLE FLOOR STRIP

Application filed March 5, 1930. Serial No. 433,316.

This invention relates to improvements in the construction of terrazzo and similar floors and more particularly refers to a new type of dividing strip adapted for use in connection with such floors.

The strips are generally made of relatively soft metal such as brass for instance, the wearing qualities of which are approximately equal to those of the floor itself; and according to the nature of the floor and of the design to be produced, the dividing strips may be of various thicknesses and lengths.

Relatively thin strips may readily be obtained out of sheet metal, and are suitable for floors of moderate size; however, relatively large floors, or floors composed of relatively large units, call for strips having sufficient rigidity to withstand the lateral pressure of the material without bulging when the floor is laid. These heavier strips are also generally made out of sheet metal but brass being expensive material, their use materially increases the cost of the floor. At times the ornamental features are such as to require extra thick metallic strips showing through the material, and in these cases, the cost is still higher.

Aside from their relatively high cost, heavy gauge strips also generally require more expensive operations and the use of heavier machines and dies for the production of anchoring and positioning means which are generally offset or otherwise obtained from the body of the strip itself.

The primary object of this invention is to provide a dividing strip of a novel and improved type suitable for use in terrazzo and like floors, said strip being provided with means adapted to support or receive an additional section or sections for the purpose of varying the thickness of the upper portion of the strip.

Another object is to provide a novel and improved construction of dividing strip for floors of the character specified, whereby the thickness of the exposed part of the strip may be varied at will merely by adding one or more sections to the main or supporting strip.

A further object of the invention is to provide a new type of dividing strip for

terrazzo and like floors comprising a main section which can of itself be used as a relatively thin dividing strip and one or more sections which may optionally be added to said main section for the purpose of increasing the width of the exposed portion of the strip, said added section or sections being made of the same or of a different metal from that used for the main section.

Other objects and advantages of the present invention will more fully appear as the description proceeds and will be set forth and claimed in the appended claims.

Various embodiments of my invention are illustrated in the accompanying drawings in which:

Fig. 1 is a fragmentary sectional view in perspective of a strip embodying my invention;

Fig. 2 is a cross vertical section of the same;

Fig. 3 is a fragmentary side view illustrating the main section of the section of the strip shown in Figs. 1, 2;

Fig. 4 is a vertical section of the same strip minus one of the additional sections;

Fig. 5 is a fragmentary plan view of a strip blank illustrating the method of producing two strip sections of the type shown in Fig. 3;

Fig. 6 is a fragmentary view in perspective of a main strip section in which the lugs or flanges for supporting the additional section are obtained by punching out portions of the body of the strip without interfering with the continuity of its lower edge;

Fig. 7 is a vertical section of said strip showing the main section and two additional sections, the edges of the supporting flanges or lugs being bent over and retaining flanges formed integral with the additional sections;

Fig. 8 is a fragmentary sectional view in perspective of a similar strip in which only one additional section is used;

Fig. 9 is a vertical section of a strip comprising a main section and two additional sections interlocking with and retained by lugs punched out of the main section, each additional section having their lower edge bent outwardly so as to produce a self anchor-

ing connection with the main section when the strip is retained in position by the floor composition;

Fig. 10 is a fragmentary view in perspective of the main section of a multiple strip in which the supporting means for an additional section or sections are obtained by laterally bending the intermediate portion of the main strip so as to form a substantially horizontal flange interposed between the upper and the lower portion of the said main section;

Fig. 11 is a fragmentary view in perspective of the same main section together with two additional sections increasing the width of the upper portion of the strip;

Fig. 12 is a fragmentary sectional view in perspective of a strip somewhat similar to that shown in Fig. 11 in which the main section is provided with means for preventing lateral displacement of the additional section or sections;

Fig. 13 is a vertical section of a strip similar to that shown in Fig. 12, having its lateral retaining means projecting beyond the edge of a flange integral with the additional section;

Fig. 14 is a vertical section of the same strip showing the lateral retaining means bent over the edge of a flange integral with an additional section;

Fig. 15 is a vertical section of a strip embodying my invention in a somewhat different form;

Fig. 16 is a vertical section of a strip comprising a main section and a relatively thin additional section retained in position by the bent over edges of lugs laterally extending from the main section;

Fig. 17 is a vertical section of a similar strip in which the same main section is used in connection with a thicker additional section;

Fig. 18 is a fragmentary vertical section of a terrazzo floor illustrating the use of a strip of the type shown in Fig. 7;

Fig. 19 is a fragmentary vertical section of a terrazzo floor illustrating the use of a strip of the type shown in Fig. 12; and

Fig. 20 is a fragmentary vertical section of a terrazzo floor illustrating the manner of using a strip of the type shown in Fig. 11, comprising only one additional section.

The structure illustrated in Figs. 1, 2, 3 comprises a main section 21 which is in itself a complete dividing strip and two additional sections 22, 23 which are combined therewith to form a strip having a relatively thick head portion and a relatively thin rib portion depending therefrom.

The main section 21 comprises an upper portion 24 having an uninterrupted upper edge 25 flush with the surface of the floor. The width of said upper portion 24 is equivalent to the depth of the upper layer of the

floor. Said main section furthermore comprises a plurality of longitudinally spaced lugs 26 depending from the upper section, and is also formed with lugs or ears 27 laterally extending from the lower edge of the upper portion at one side thereof, and with similar lugs or ears 28 laterally extending therefrom at the other side.

The outer edges 29 of said lugs or ears are shown bent upwardly and since all the ears on one side are in longitudinal alignment with one another, they collectively form a longitudinal support upon which an additional section may be placed in order to increase the width of the exposed portion of the strip.

The additional sections 22, 23 are shown in the form of angles comprising a vertical rib member such as 30 the height of which corresponds to the distance of the upper surface of the lugs 27, 28 and the upper edge 25 of the main section, and a flange such as 31 laterally extending from the lower edge thereof, the width of said flange corresponding to the distance between the lateral surface of upper portion 24 of the main section and the inner surface of turned up edges 29 of lugs or ears 27, 28.

By virtue of this construction it is possible to place the main section in position in the ordinary manner when the floor is laid, the lower surface of lugs 27, 28 resting upon the surface of the lower layer of the floor, and lugs 26 projecting through said lower layer. Before the material composing the upper layer is spread in position, additional sections 22, 23 are placed upon the ledges formed by lugs or ears 27, 28 respectively, so that when the upper layer of the floor is laid in position, said additional sections will be automatically anchored by their flange portions 31.

It will be observed that if the main section only is used, the thickness of the metal strip showing through the floor material will be equivalent to the thickness of said main section; if only one additional section 22 is used as shown in Fig. 4 the width of the lines showing through the floor material will be equivalent to the combined thickness of the main strip and the additional strip; and if another additional section 23 is also used as shown in Figs. 1, 2, then the width of said lines will be further increased by the thickness of said section 23.

It is, of course, possible to use additional sections of various widths so that a number of combined widths can be obtained according to requirements to be fulfilled in each case. It is also obvious that the additional sections may be made out of metals or materials different from that out of which the main section is made so that various color combinations may be obtained. Furthermore, if the additional section or sections are

made of material having anti-slip properties the resulting floor will also acquire anti-slip properties, as I have explained in another patent entitled Method of and means for 5 producing anti-slip terrazzo floorings, granted to me January 7, 1930, Patent #1,742,855.

In the construction shown the total width of each lug or ear 27—28 including its upturned edge 29 is equivalent to half the height 10 of lugs 26 and the width of notches 32 intervening between adjoining lugs 26 is equivalent to the length of one lug or ear 27 plus the length of one adjoining lug or ear 28; plus the width of one lug 26, so that before 15 said adjoining ears or lugs 27, 28 are bent outwardly notches have a stepped outline symmetrical with and opposite to the stepped outline of the combined unbent lugs or ears and a lug 26 adjoining thereto.

20 This feature is clearly illustrated in Fig. 5 where it is seen that a strip blank 33, the width of which is equivalent to twice the height of upper portion 24, plus the height of lugs 26, is divided into two blank main sections by a line comprising longitudinally spaced S sections such as 34 joined by longitudinal straight sections such as 35, the width of said S sections corresponding to the height of lugs 26 and their height corresponding to twice the width of lugs 26 and the length of sections 35 corresponding to the combined length of adjoining lugs or ears 27, 28. The S sections are completed by 25 extending their end tracts to points in alignment with their longitudinal tracts 36, 37 by slitting the material as shown at 38, 39, 38', 39'. The material is furthermore slit in a transversal direction midway of the length of each longitudinal section 35 between points 40 such as 40, 41 in alignment with longitudinal tracts 36, 37, of the S sections as shown at 42.

In this manner, the portion of material intervening between adjoining S sections is divided into four lugs having their edges exposed along three sides, said lugs remaining 45 integral with the two upper portions 24', 24" of the resulting main strip sections and being bendable along longitudinal lines in alignment with longitudinal tracts 36, 37 of the S 50 sections as shown in dotted lines at 43, 44.

In this manner two complete main section blanks can be obtained from a single strip blank the width of which is less than twice the height of said main sections without wasting any material, this method of production being in accordance with that described and claimed in another patent application entitled Methods of producing dividing strips for floors, filed simultaneously herewith.

60 The main section may also be formed out of a strip blank having uninterrupted upper and lower edges, if desired. Such a construction is illustrated in Figs. 6, 7, 8, in which 45 designates the body of the main strip section, 65 the same being punched at longitudinal in-

tervals to form openings such as 46, 47, by bending outwardly ears or lugs 48, 49, defined by said openings, along the upper edge of said openings.

In Fig. 6 lugs 48, 49 are shown alternately extending at one side and then at the other from the body of the strip and their outer edges are shown upturned as at 50 and having a height permitting of their upper edge portions being further turned inwardly so as to form a groove or clearance space between said inwardly turned edge portion and the laterally extending main portion.

This construction is shown in Fig. 8 where it is seen that by thus bending inwardly upper edge 50' of upwardly turned portions 50 of ears or lugs 48, it is possible to securely lock in position the horizontal flange portion 51 of additional section 52 placed upon the ledge formed by lugs or ears 48.

35 In a similar manner it is possible to securely lock in position another additional section at the opposite side as shown in Fig. 7 where 45 is the main section, 52' is an additional section corresponding to section 52 shown in Fig. 8 and 53 is an additional section placed at the opposite side of the main section.

40 In the arrangement shown in Fig. 9, the main section 54 is provided with hook formed lugs or ears 55, 56 which extend laterally therefrom at an angle of less than 90 degrees, said ears or lugs forming longitudinal ledges adapted to receive and support additional upper sections 57, 58 which like in the previous cases comprise vertical rib portions such as 58 and a flange portion such as 60 which is obtained by bending outwardly the inner edge of said additional sections at an angle corresponding to the angle of lugs or ears 55, 56.

45 This method of construction makes it easier to use heavier gauge strips for additional sections, 57, 58, a lighter bending operation being required.

50 The inventive idea may be applied in ways different from those so far shown and described. For instance, in Figs. 10, 11 I show a strip comprising a main section 61 which comprises an upper portion 62 and a lower portion 63 integral therewith and laterally offset therefrom, the inner edges of said two portions being joined by an intermediate horizontal flange portion 64 obtained by bending a strip blank along two longitudinal lines 65, 66.

55 A main section thus formed can be used as a self anchoring strip when relatively thin lines are to be produced in the floor, or else it can be used in combination with an additional section or sections, 67, 68, consisting of angle shaped bars laid on top of flange portion 64, said bars having their upper edges level with each other and with the up-

per edge 69 of the main section, when placed in nested relation as shown.

It is also possible to provide lateral rests for the additional sections by punching out of the intermediate flange portion lugs such as shown at 70 in Fig. 12 at spaced intervals, said lugs being obtained by turning upwardly tongues isolated by openings 71 produced in said flange portion 72 adjacent the lower portion which in this case is shown comprising a longitudinal bar 73 and a plurality of spaced lugs 74 depending therefrom.

This construction provides a channeled ledge support for the additional section 75 similar to the ledge provided by lugs 27, 28 in Figs. 1, 2, 3, 4, preventing lateral displacement of said additional section 75. The lugs thus obtained can also be made to project beyond the upper edge of the flange portion 20 of the additional section abutting thereagainst, so that their upper edges can be turned inwardly over said flange so as to securely lock the additional section or sections in position.

Such a construction is shown in Figs. 13, 14 where the main section is shown composed of an upper portion 76, a lower portion 77 and an intermediate horizontal flange portion 78 punched at intervals to form openings 79 isolating tongues 80 which are turned upwardly as shown in Fig. 13 and the upper edges of which are turned inwardly after an additional section 81 has been placed in position so as to bend over the flange portion 82 of said additional section securely locking the same in position as shown in Fig. 14.

A channeled ledge effect can be obtained without weakening the section of the strip by punching it at intervals by upturning the bent edge formed at the point where the horizontal flange meets the lower portion of the strip. Such an arrangement is illustrated in Fig. 15 where it is seen that the main section comprises an upper portion 83, a lower portion 84 and an intermediate horizontal flange portion 85, the edge 86 where portions 84, 85 reach above the level of flange 85 thus forming a channeled support for an additional section 87.

As stated before, the construction advocated lends itself to the use of additional sections of varying widths in combination with a standard main section. For instance, in Fig. 16 I illustrate a main section 88 of the type shown in Fig. 8 in combination with a relatively thin section 89 added thereto and locked in position by the downturned edges 90 of ears or lugs 91. In Fig. 17 I show the same main section in combination with a relatively thick section 92, also placed on the ledge formed by lugs or ears 91 said section 92 being also locked in position by downturned edges 90 of ears or lugs 91, the flange portion of said additional sections 89, 92

having the same thickness and width at the base.

In Fig. 18, 93 designates a floor foundation, 94 the lower layer of a terrazzo floor and 95 the upper layer. The same figure illustrates the use of a strip of the type shown in Figs. 6, 7 and from the same it will be observed that the lower surface of the lugs or ears is on a level with the upper surface of the lower layer of the floor thus determining the depth at which the strip is to be placed, the upper surface 96 of the strip being level with the upper surface 97 of the floor.

In a similar manner, Fig. 19 illustrates the use of a strip of the type shown in Fig. 12 where it is seen that the lower surface of the flange portion 98 rests upon the upper surface of the lower layer of the floor 99 thus acting as a positioning means for the strip determining the thickness of the upper layer 80 85 100.

In Fig. 20, I illustrate the use of a strip of the type shown in Fig. 11 comprising a main section 101 and an additional section 102 placed in a floor comprising an upper layer 103 and a lower layer 104 laid on top of a foundation bed 105.

It will be observed that the construction advocated results in the production of strips of great rigidity and strength requiring a relatively small amount of labor for their manufacture. The invention furthermore possesses the advantage of a great flexibility, affording means for producing a considerable variety of different strips merely by varying the nature and number of the additional sections used in connection with a main section of standardized design. This makes it possible to reduce to a minimum the investment required for tools, dies and other means of manufacture and also makes it possible to reduce to a minimum the stock to be kept on hand, for the production of strips suitable for various purposes and requirements.

The constructional details of my improved strip may further vary from those shown without departing from the inventive idea; the drawings will therefore be understood as being intended for illustrative purposes only and not in a limiting sense. Accordingly, I reserve the right to carry my invention into practice in all those ways and manners which may enter, fairly, into the scope of the appended claims.

I claim:

1. A dividing strip for terrazzo floors or the like, comprising a main strip section provided with laterally extending supporting means adapted to support additional sections, and additional section retaining means, integral with said strip, projecting upwardly of the outer edge of said supporting means, said main section having an uninterrupted upper edge level with the surface of a floor 120 125 130

in which the strip is used, and being adapted per se to be used as a complete strip.

2. A dividing strip for terrazzo floors and the like, comprising a main strip section provided with laterally extending supporting means, said main section having an uninterrupted upper edge level with the surface of a floor in which the strip is used, and an additional section supported upon said supporting means, said additional section also having its upper edge level with the surface of the floor, and producing with said main section, a combined strip the upper portion of which has a greater thickness than the upper portion of said main section.

3. A dividing strip for terrazzo floors and the like, comprising a main strip section provided with laterally extending supporting means, said main section having an uninterrupted upper edge level with the surface of a floor in which the strip is used, and an additional section supported upon said supporting means, said additional section also having its upper edge level with the surface of the floor, and producing with said main section, a combined strip the upper portion of which has a greater thickness than the upper portion of said main section, and means preventing lateral displacement of said additional section.

4. A dividing strip for terrazzo floors and the like, comprising a main strip section provided with laterally extending supporting means, said main section having an uninterrupted upper edge level with the surface of a floor in which the strip is used, and an additional section supported upon said supporting means, said additional section also having its upper edge level with the surface of the floor, and producing, with said main section, a combined strip the upper portion of which has a greater thickness than the upper portion of said main section, and means integral with said supporting means, preventing lateral displacement of said additional section.

5. A dividing strip for terrazzo floors and the like, comprising a main strip section provided with laterally extending supporting means, said main section having an uninterrupted upper edge level with the surface of a floor in which the strip is used, and an additional section supported upon said supporting means, said additional section also having its upper edge level with the surface of the floor, and producing, with said main section, a combined strip the upper portion of which has a greater thickness than the upper portion of said main section, and means for locking said additional section in position.

6. A dividing strip for terrazzo floors and the like, comprising a main strip section provided with laterally extending supporting means, said main section having an unin-

terrupted upper edge level with the surface of a floor in which the strip is used, and an additional section supported upon said supporting means, said additional section also having its upper edge level with the surface of the floor, and producing, with said main section, a combined strip the upper portion of which has a greater thickness than the upper portion of said main section, and means integral with said supporting means, locking said additional section in position.

7. A dividing strip for terrazzo floors and the like, comprising a main strip section provided with supporting means laterally extending therefrom at each side thereof, said main section having an uninterrupted upper edge level with the surface of a floor in which the strip is used, and an additional section at each side of said strip, supported upon said supporting means, each of said additional sections also having its upper edge level with the surface of the floor, and producing, with said main section, a combined strip the upper portion of which has a greater thickness than the upper portion of said main section.

8. A dividing strip for terrazzo floors and the like, comprising a main strip section provided with supporting means laterally extending therefrom at each side thereof, said main section having an uninterrupted upper edge level with the surface of a floor in which the strip is used, and an additional section at each side of said strip, supported upon said supporting means, each of said additional sections also having its upper edge level with the surface of the floor, and producing, with said main section, a combined strip the upper portion of which has a greater thickness than the upper portion of said main section, and means preventing lateral displacement of said additional sections.

9. A dividing strip for terrazzo floors and the like, comprising a main strip section provided with supporting means laterally extending therefrom at each side thereof, said main section having an uninterrupted upper edge level with the surface of a floor in which the strip is used, and an additional section at each side of said strip, supported upon said supporting means, each of said additional sections also having its upper edge level with the surface of the floor, and producing, with said main section, a combined strip the upper portion of which has a greater thickness than the upper portion of said main section, and means integral with said supporting means preventing lateral displacement of said additional sections.

10. A dividing strip for terrazzo floors and the like, comprising a main strip section provided with supporting means laterally extending therefrom at each side thereof, said main section having an uninterrupted upper edge level with the surface of a floor in which

the strip is used, and an additional section at each side of said strip, supported upon said supporting means, each of said additional sections also having its upper edge level with the surface of the floor, and producing, with said main section, a combined strip the upper portion of which has a greater thickness than the upper portion of said main section, and means integral with said supporting means locking said additional sections in position.

11. A dividing strip for terrazzo floors and the like, comprising a main strip section provided with laterally extending supporting lugs, said main section having an uninterrupted upper edge level with the surface of a floor in which the strip is used, and an additional section supported upon said supporting lugs, said additional section also having its upper edge level with the surface of the floor, and producing, with said main section, a combined strip the upper portion of which has a greater thickness than the upper portion of said main section, the outer edges of said lugs being bent over parts of said additional section, securely locking said additional section in position.

12. A dividing strip for terrazzo floors and the like, comprising a main strip section provided with laterally extending supporting lugs, said main section having an uninterrupted upper edge level with the surface of a floor in which the strip is used, and an additional angle section supported upon said supporting lugs, said additional section also having its upper edge level with the surface of the floor, and producing, with said main section, a combined strip the upper portion of which has a greater thickness than the upper portion of said main section, the outer edges of said lugs being bent over the edge of the base flange of said additional section, securely locking said additional section in position.

13. A dividing strip for terrazzo floors and the like, comprising a main strip section provided with supporting lugs laterally extending therefrom at each side thereof, said main section having an uninterrupted upper edge level with the surface of a floor in which the strip is used, and an additional section at each side of said strip, supported upon said supporting lugs, each of said additional sections also having its upper edge level with the surface of the floor, and producing, with said main section, a combined strip the upper portion of which has a greater thickness than the upper portion of said main section, the outer edges of said lugs being bent over parts of said additional sections, securely locking said additional sections in position.

14. A dividing strip for terrazzo floors and the like, comprising a main strip section provided with supporting lugs laterally extending therefrom at each side thereof, said main section having an uninterrupted upper edge level with the surface of a floor in which the

strip is used, and an additional angle section at each side of said strip, supported upon said supporting lugs, each of said additional sections also having its upper edge level with the surface of the floor, and producing, with said main section, a combined strip the upper portion of which has a greater thickness than the upper portion of said main section, the outer edges of said lugs being bent over the edge of the base flange of said additional sections, securely locking said additional sections in position.

15. The method of producing dividing strips for terrazzo floors and the like, said strips having their upper edges of varying widths, which consists in placing against the side of, and supporting upon a main section, an additional section or sections the upper edge of which is level with the edge of said main section so as to increase the width thereof.

16. The method of producing dividing strips for terrazzo floors and the like, said strips having their upper edges of varying widths, which consists in placing against the side of, and supporting upon a main section, an additional section or sections the upper edge of which is level with the edge of said main section so as to increase the width thereof, and securely locking said additional section or sections in position.

17. A dividing strip for terrazzo floors or the like, comprising a main strip section provided at a point intermediate its upper and lower edges, with laterally extending supporting means adapted to support additional sections, and additional section retaining means, integral with said strip, projecting upwardly of the outer edge of said supporting means, said main section having an uninterrupted upper edge level with the surface of a floor in which the strip is used, and being adapted per se to be used as a complete strip.

18. A dividing strip for terrazzo floors or the like, comprising a main strip section provided at a point intermediate its upper and lower edges, with laterally extending supporting means adapted to support additional sections, and additional section retaining means, integral with said strip, projecting upwardly of the outer edge of said supporting means, said main section having an uninterrupted upper edge level with the surface of a floor in which the strip is used, and being adapted per se to be used as a complete strip, said laterally extending supporting means acting as positioning means for the strip determining the depth at which the strip is to be inserted within the floor composition.

19. A dividing strip for terrazzo floors and the like, comprising a main strip section provided with laterally extending supporting means, said main section having an uninterrupted upper edge level with the surface

of a floor in which the strip is used, and an additional section supported upon said supporting means, said additional section also having its upper edge level with the surface of the floor, and producing with said main section, a combined strip the upper portion of which has a greater thickness than the upper portion of said main section, said laterally extending supporting means acting as positioning means for the strip determining the depth at which the strip is to be inserted within the floor composition.
